UNITED STATES PATENT OFFICE.

PETER C. FILBERT, OF LOS ANGELES, CALIFORNIA.

MAIL-CATCHER.

1,120,297.

Specification of Letters Patent.

Patented Dec. 8, 1914.

Application filed February 25, 1914. Serial No. 820,945.

To all whom it may concern:

Be it known that I, PETER C. FILBERT, a citizen of the United States, residing at Los Angeles, in the county of Los Angeles and State of California, have invented certain new and useful Improvements in Mail-Catchers, of which the following is a specification.

This invention relates to a mail catcher, and the principal object of the invention is to provide a receptacle which may be mounted adjacent the railroad track which will receive the mail sack and protect the sack from the weather.

Another object of the invention is to provide an improved type of receptacle having pivotally mounted therein a resilient abutment which limits the passage of the sack through the receptacle and prevents the sack from striking the bottom of the receptacle with a violent blow.

Another object of the invention is to provide improved guide ways for guiding the sack into the receptacle.

Another object of the invention is to provide an improved type of cover for the receptacle, the cover being held in place by the rod which supports the pivotally mounted bumper.

This invention is illustrated in the accompanying drawings wherein—

Figure 1 is a vertical longitudinal sectional view through the mail catcher; Fig. 2 is an end elevation of the mail catcher; Fig. 3 is a transverse sectional view through the mail catcher taken along the line 3—3 of Fig. 1.

The body portion 10 of this receptacle which forms the chamber in which the mail bag 11 passes is supported by the legs or standards 12 and has its end walls provided with outwardly-extending supporting flanges 13. The side walls of the body portions extend above the end walls and form flanges 14 which prevent the superstructure of the receptacle from moving transversely upon the body portion. This superstructure or frame 15 rests upon the flanges 13 and has its bottom provided with an opening 16 through which the mail sack may pass in order to drop into the body portion 10. The end walls of the superstructure are provided with inlet openings and the side walls are carried above the end walls with their upper end portions tapered thus constituting bearings for the pivot rod 16. The cover 17 fits

within the walls of the superstructure and has its side walls 18 provided with slots 19 through which the rod 16 may pass in order to removably mount the cover. Guide plates 20 rest upon the bottom of the superstructure or frame 15 and have their inner end portions bent to form hooks 21 which extend through the opening in the bottom of the frame and engage the end walls of the body portion 10 to limit the outward movement of the guide plates.

Side flanges 22 extend upwardly from the outer end portions of the guiding plates 20 and have their upper edge portions extending through slits formed in the end walls of the frame 20 to brace the flanges 22 and prevent them from being bent by a mail sack striking them. An abutment or bumper is pivotally mounted upon the rod 16 and hangs in the mail catcher in the position shown in Fig. 1. This bumper is formed from a plate of resilient material such as spring steel which is bent intermediate its length to form the bearing 23 from which there extends the two leaves 24. These leaves 24 extend in diverging relation with their lower ends extending into the body portion 10 to such an extent that when the bumper is moved toward one end 85 of the mail catcher, one of the leaves will strike the hooked end 21 of one of the guiding plates 20 and thus prevent the bumper from swinging beyond the desired amount.

The operation of this device is as follows: 90 This mail catcher is mounted adjacent the track with the side walls of the catcher extending parallel to the track and with the flanges 22 positioned upon the far side of the mail catcher. The cover 18 may be put in place upon the rod 16 or if desired may be left off. It is better, however, to have this cover in place so that rain and snow will be prevented from entering the body portion 95 of the mail catcher. As a train passes the 100 station, the mail sack may be thrown into the catcher or may be suspended from suitable supporting means so that the sack will be in the proper position to pass into the mail catcher. As this mail sack passes into 105 the mail catcher through one end thereof, it will strike the abutment or bumper and will swing the same until one of the leaves strikes the hook 21. The leaf of the bumper which is engaged by the mail sack will then 110 take up the force of the blow and the sack will drop into the body portion 10. It is

not necessary to immediately remove the sack after deposited since when the sack drops into the body portion, the bumper will return to its normal position and the mail catcher is then ready for further use. As soon as desired the door 25 may be opened and the mail sack removed. This mail sack can not very easily fail to pass into the mail catcher since the flanges 22 prevent the mail sack from passing off of the guiding plates 20 without passing into the mail catcher.

What is claimed is:

1. A mail catcher comprising a body portion having an open upper end, a superstructure carried by said body portion and having its bottom provided with an opening for permitting communication with said body portion and having its end walls provided with inlet openings, a pivot rod carried by said super-structure, and an abutment pivotally mounted upon said pivot rod and provided with resilient arms extending in diverging relation through the opening in the

bottom of said superstructure and into said body portion, said arms being of such length 25 that the pivotal movement of said abutment will be limited.

2. A mail catcher comprising a body portion having an open upper end, a superstructure carried by said body portion and 30 having its bottom provided with an outlet opening and having its end walls provided with inlet openings and an abutment pivotally connected with said superstructure and provided with resilient arms extending 35 in diverging relation through the outlet opening of said superstructure into said body portion, said arms being of such length as to limit the pivotal movement of said abutment.

In testimony whereof I affix my signature in presence of two witnesses.

PETER C. FILBERT.
